UNITED STATES PATENT OFFICE.

EDWIN FISHER, OF BOSTON, ASSIGNOR TO THE LOWELL MANUFACTURING COMPANY, OF LOWELL, MASSACHUSETTS.

DESIGN FOR A CARPET.

SPECIFICATION forming part of Design No. 12,397, dated August 2, 1881.

Application filed July 5, 1881. Term of patent 3½ years.

To all whom it may concern:

Be it known that I, EDWIN FISHER, of the city of Boston, county of Suffolk, and State of Massachusetts, have invented and produced a new and original Design for a Pattern to be Inwrought in Two or Three Ply Ingrain and other Carpeting in such colors as may be desired; and I do hereby declare that the photographic print accompanying this specification conveys to any one skilled in the art of carpet-weaving a clear understanding of the same, and is sufficient to enable such person to use my invention.

What I claim as my invention, and desire to secure by Letters Patent, is—

The design for ornamenting ingrain or other carpeting, as shown in the photographic print accompanying this specification.

EDWIN FISHER.
